UNITED STATES PATENT OFFICE.

JOHN FREDERIC HESSEL, OF CHAMPAIGN, ILLINOIS.

HARNESS-PAD.

SPECIFICATION forming part of Letters Patent No. 286,435, dated October 9, 1883.

Application filed January 20, 1883. (No model.)

To all whom it may concern:

Be it known that I, JOHN FREDERIC HESSEL, of Champaign, in the county of Champaign and State of Illinois, have invented 5 certain new and useful Improvements in a Harness-Pad; and I do hereby declare that the following is a full, clear, and exact description thereof, reference being had to the accompanying drawings, and to the letters of reference marked thereon, which form a part of this specification, in which—

Figure 1 is a vertical section taken through my improved harness-pad in a direction with respect to its length. Fig. 2 is a top view of 15 the harness-pad. Fig. 3 is a perspective view of the saddle-plate and hook detached from the pad. Fig. 4 is a bottom view of one of the side pad-plates. Fig. 5 is a perspective view of one of the girth-rings and its plate. 20 Similar letters of reference indicate corresponding parts in the several figures.

This invention relates to novel improvements on harness-pads or "saddles;" and the nature of my invention will be fully understood from the following description, when taken in connection with the annexed drawings.

A designates the upper leather portion of the saddle, and B B the padded portion. 30 C C are the metal plates or frames of the saddle; D D, the leather covering thereof; E E, the terrets which pass through the frames C C and leather portion A, and which have secured to their inner ends nuts that are 35 inclosed in the padded portions.

F F are girth-loops, which are secured to plates G G, fastened to the outer ends of the frames C C; and J is a saddle-plate, which is connected flexibly to the inner ends of the 40 said frames. This saddle-plate J is a rigid casting. The crupper-strap loop a is cast on the back edge of the plate J, and a lip, b, is cast on its front edge. To the bottom of the plate J a spring-plate, K, is secured by the 45 shank of the check-rein hook L and a nut, which spring-plate extends beyond the sides of the plate J, and is perforated to receive through it screws c c, that are used to secure the upper ends of the frames C C to the portion A. The plate J is perforated at d d d to receive studs e, which are cast on the under sides and near the inner ends of the frames C C. 50

The saddle-plate J is by the above means

secured flexibly to the pad or saddle, and affords a solid base for the attachment of the 55 hook L to the saddle, and allows the use of any desired style of hook.

It will be observed that the inner ends of the frames C C cover the sides of the plate J and form a very neat finish. At the same 60 time flexibility is allowed at the joints of the parts.

The girth-loops F are pivoted to the plates G, and these plates are secured to the frames C by means of screws g, and also by means 65 of studs h, cast on the frames C. Thus it will be seen that should the screws g work loose and become detached from the harness-pad and the studs h will prevent the loops and their plates from slipping out of their places. 70

It will be seen from the above description that I have a flexible pad made partly of leather and partly of metal, the metal part being composed of sections so united as to admit of the required flexibility of the pad 75 and its consequent adaptability to the back of a horse.

I have shown the studs e on the upper ends of the plates or frames C perpendicular to the planes thereof; but, if desired, these studs 80 may be inclined either toward the center of the pad or from the center. I may also form shoulders on the ends of the studs e and rivet the plates C loosely to the central plate.

Having described my invention, what I 85 claim as new, and desire to secure by Letters Patent, is—

1. The combination, in a harness-pad, of the plate J, the spring-plate K, and the hook L, secured together and attached to the 90 frames C C, and leather portion A, all substantially in the manner and for the purposes described.

2. The combination, in a harness-pad, of the cast-metal frame C, the studs e, screw-fastenings e, and the plate J, all constructed and adapted to operate substantially in the manner and for the purposes described. 95

In testimony that I claim the foregoing as my own invention I affix my signature in 100 presence of two witnesses.

JOHN FREDERIC HESSEL.
